UNITED STATES PATENT OFFICE.

ALEXANDER D. JOSLIN, OF CHICAGO, ILLINOIS.

HAND-STAMP.

SPECIFICATION forming part of Letters Patent No. 373,589, dated November 22, 1887.

Application filed May 1, 1886. Serial No. 200,813. (No model.)

To all whom it may concern:

Be it known that I, ALEXANDER D. JOSLIN, a citizen of the United States, residing in Chicago, in the county of Cook and State of Illinois, have invented a new and useful Improvement in Hand-Stamps, of which the following is a specification.

My invention relates to hand-stamps for railroad-tickets; and its object is to provide a hand-stamp for simultaneously stamping or printing upon the face of a railway-ticket the name of the destination-station, the class or character of the ticket, the day, month, and year, indicating the date when sold, as well as the name of the railway-company by whom it is sold, or any other desired data, my improved stamp being specially designed for coupon-tickets, wherein it is desirable that such data should appear upon each separate coupon. In such coupon-tickets heretofore it has been customary either to specially write the name of the destination upon each one or part of the coupons, or else to print upon the margin of each coupon as large a list as possible of names of stations on the terminal line, and then designate the particular station for which the ticket is sold by punching, if its name appears on the list. The punching of each coupon in this way requires time; but it is obviously impracticable to thus print on the margin of the coupon the names of all the stations required, and, in fact, only comparatively few of them—the more important ones—are in practice so printed. In railroad-ticket stamps heretofore also the date of the ticket, name of station where sold, &c., have been printed on the back of the ticket. This, for obvious reasons, is somewhat inconvenient. By my present improvement all necessary data may be simultaneously stamped on the face of the ticket.

My invention consists in the novel devices and novel combinations of devices herein shown and described, and more particularly pointed out in the claims.

In the accompanying drawings, which form a part of this specification, and in which similar letters of reference indicate like parts, Figure 1 is a side elevation of a device embodying my invention. Fig. 2 is a plan view, the plunger-arm being sectioned. Fig. 3 is a bottom view. Fig. 4 is a central vertical longitudinal section. Figs. 5, 6, and 7 are detail

views of the type-ring-holding key or device. Fig. 8 is a detail central section of the type-rings and their shaft. Fig. 9 is a detail perspective view of the movable type-wheel stop. Figs. 10 and 11 are detail views of one of the ribbon-spools. Fig. 12 is a view showing the adjustable notch in the type-ring key lengthened; and Fig. 13 shows a ticket as stamped by the machine when the ticket is passed transversely through the machine, so that the lines run in the direction of the length of the ticket.

In said drawings, A and A' represent the frame of the machine, which is cast in two parts with two transverse partitions, A² A², therein.

B is the type-ring shaft, journaled on the frame A A', having an enlargement or barrel, b, upon which the type-rings D D, furnished with type, d, and intervening notches, d', on their peripheries, are mounted.

E are washers interposed between the type-rings D and secured to the shaft B or its enlargement b by tongues or projections e which fit in a groove, b', on said barrel b for the purpose of affording a frictional connection between each of the type-rings and the shaft B, so that each of the type-rings may be turned to any desired position by revolving the shaft B, and then fixed in position while other type-rings are in like manner being adjusted by revolving said shaft B. Each type-ring D after being adjusted is held in position by a sliding key, F, which moves back and forth in a suitable slot, f, in the base block or frame A, and which is furnished with a notch or recess, f', to permit the type-ring to revolve when it registers with said notch.

When but few letters or type-rings are required to form the name of a station, it is desirable to quickly and simultaneously turn all the remaining type-rings to their blanks. To accomplish this I provide means for increasing the extent or width of the notch f' in the key F, so that a number of the type-rings may be turned at once by the shaft B. This is most conveniently done by mounting a second or supplemental slide, f², in a guide or groove, f³, in the key F, which slide f² forms one of the end walls of the notch f'. By withdrawing the slide f² on the key F the width of the notch f' may be increased to the desired ex-

tent. The handle F' of the key F is pivoted to this slide f², and it is furnished with a pin or projection, f⁴, which fits in a corresponding recess, f⁵, in the key F, whereby the slide 5 f² is held in place on said key. A pin or projection, f⁶, on the slide f² fits in a slot, f⁷, in the side of the key F and serves to guide and retain the slide f² in place.

G is a sliding block having a series of thin 10 blade-like fingers or stops, g, which project between the type-rings D, so that their ends may strike against pins or projections d² on the sides of the type-rings, and thus stop each type ring when turned so that its blank type 15 will register at the printing line or point. These pins d² in each type-ring D fit in corresponding annular grooves, d³, in the adjacent type-ring. After a word has been set up, all 20 the unused type-rings may be simultaneously turned to their blank spaces by simply pulling out the slide f² on the key, thus extending the notch f', and then pushing in the block G, so that the fingers g will stop the type-rings at the right point by striking against the pins d². 25 The block G is furnished with a suitable handle, g', which passes through a slot, g², in the case H, which surrounds the block G and the curved end of the frame A A'.

In setting the type-rings and moving the 30 key F back the thickness of each successive type-ring as it is turned to position to bring the desired letter or type to place, it greatly facilitates the operation to have some device to regulate or measure the movement of the key 35 F, so that its notch f' may be quickly brought to register with the type-ring. This I do by providing the key with a series of notches, f⁸, in which fits a spring-pawl, f⁹, having a double-inclined projection or bent end, f¹⁰, so that 40 it will readily allow the key to move in either direction. This spring-pawl is secured to the cross-bar in which the key F is mounted, and it not only registers each successive movement of the key, but it also serves to limit each 45 movement or cause the notch f' on the key to register with each successive type-wheel as the key is moved.

K is a small rotary type shaft or cylinder arranged parallel to the type ring shaft B and 50 mounted on the frame A'. This cylinder prints the word or words indicating the class or character of the ticket, as "unlimited," "special," "theater," "1st class," "2d class," &c. The cylinder should have as many printing-faces 55 k as there are classes to be designated, the type being fixed or rigid. The handle or disk K' for turning this type-cylinder K is furnished with similar faces, k', with characters indicating the word or words on the corresponding printing-faces, k. The cylinder K is 60 also provided with a head, K², having flat faces k², against which fits a flat-headed spring-pin, k³, mounted in a socket, k⁴, on the frame A'. The faces k² correspond to the printing-faces 65 on the cylinder, and the spring-pin thus serves to hold the printing-faces in position, and still permit the cylinder to be readily turned when

desired. The spring k⁵ fits in the bottom of the socket k⁴ and bears against the end of the pin k³. The shaft K has its bearings in suitable slots in the frame A', and is held therein by the face-plate L, which fits on top of the frame A'.

The dating-wheels N N' N², to print the month, day, and year, respectively, are 70 mounted on a shaft, M, arranged at right angles to the type-wheel shaft B and the class-printing cylinder K. The wheel N', which is furnished with types or characters for printing the days of the month from 1 to 31, is fixed 80 rigidly to the shaft M, so that it may be turned by the hand-wheel M' on the end of said shaft. The shaft is also furnished with an indicating wheel or disk, n, the rim of which projects up through a slot, l, in the face plate, and is furnished with figures corresponding to those on the dating-wheel N', so that the operator may readily see when the wheel is properly set. The wheel n is provided with a series of notches, n', cut in the periphery of the shoulder n² thereon, in which notches a spring pawl, n³, having a bent end, n⁴, fits for the purpose of holding the type-wheel N in position. The bent end n⁴ of the pawl n³ is similar to the bent end f¹⁰ of the pawl f⁹. The bent end of the 90 pawl permits the shaft M to be turned in either direction. The month-printing wheel N, as well as the year-printing wheel N², is loose upon the shaft M. They of course require to be seldom moved, and are turned or set by 100 hand. These wheels are provided on their outsides with circular shoulders n⁵ n⁶, in which are cut notches n⁷ n⁸, that engage spring-pawls n⁹ n¹⁰ for holding the wheels in proper position for printing. These wheels N N' N² fit 105 between the cross plates or partitions A² A², cast on the frame A A', and said plates serve to hold the wheels N and N² in place.

As the shafts B and M are not both in the same plane or on the same level, the meeting 110 line a of the frame parts A A' has a jog, a', at the end of the shaft M, so that the bearings of both said shafts may lie half in each part of said frame. This materially facilitates putting the apparatus together and taking it apart, as 115 well as simplifies the construction of the shafts and the parts secured thereto.

The name of the station where the stamp is used or the ticket sold, as well as that of the railroad selling the ticket, do not need to be 120 changed on any particular machine, and both these names I therefore stamp by appropriate characters or type cut on the die-plate O, surrounding the dating-wheels N N' N². This die-plate fits upon and is secured rigidly to the 125 partition-plates A² A².

P and Q are the ribbon-spools. The shaft p of the former is journaled in the frame A' and passes through the spool. The spool is prevented from turning on the shaft by a pin or projection, p', on the shaft, which fits in a notch in the spool. A spiral spring, p², surrounding the shaft p, prevents the spool from turning too easily, and thus keeps a proper tension on 130

the ribbon P'. The other spool is of a similar construction and its shaft q is journaled in the case Q', inclosing the spool, and which is secured by a rod or pin, q', to the end of the face-plate L or projecting ears l' thereon. The rod q' passes through holes in the ends of the case Q' near their periphery, and one end of said rod is threaded and enters a threaded hole in one of the ears l'. The case Q is furnished 10 with a slot, q'', for the ribbon to pass through, and the rod q' serves also as a guide-bar for the ribbon.

The face-plate L is provided with an opening, l', for the destination-printing type-rings 15 D to project through, and another opening, l'', for the class-printing cylinder K, the dating-wheels N N' N'', and the die-plate O. The ribbon P' passes from the spool Q under the guide-rod q', under the end of the face-plate, over the type-rings D, under the cross-bar l' of the face-plate, over the cylinder K, dating-wheels N N' N'', and die-plate O to the other spool, P.

The type-rings D, having indicating letters d' cut in the notches or recesses d' corresponding to the type d and the curved end plate, H, is furnished with a window or slot, h, so that by the letters d' in the notches d' the particular type at the printing-point may be indicated.

30 R is the plunger. It is of the usual and may be of any ordinary construction. The plunger is mounted on a curved projecting arm, A⁴, cast on the frame A' and having a forked base, A⁵. The forked base A⁵ forms an opening, A⁶, between the branches or limbs of the fork, through which opening the ticket to be stamped may be passed or inserted when desired. This opening A⁶ enables the ticket to be passed longitudinally through the machine, 40 so that the lines of printing may thus be made to extend crosswise of the ticket, if desired. This is sometimes desirable; but ordinarily, however, the ticket will be passed transversely through the machine, or in the direction of the 45 lines of printing or type, so that the printed lines on the ticket will extend longitudinally thereon, as indicated in Fig. 13.

In the ticket shown in the drawings the name "Rochester" at the top indicates the 50 destination-station, and this name is set up from the type-rings D and printed by them. The words "First Class" are printed by the cylinder K, "Cairo" and "I. C. R. R." by the die-plate O, and the date "April 22, 1886" 55 by the dating-wheels N, N', and N''. In addition to these words thus stamped upon the ticket it also, of course, contains the usual or any desired characters printed thereon.

The two parts A and A' of the frame are 60 secured together by screws a², which enter threaded holes in the frame part A'. The screws a² are four in number and enter from the bottom, as indicated in Fig. 3 and also in Fig. 1, where one of the screws is shown in 65 dotted lines. The screw passes through a smooth hole in the lower frame part, A, and

its threaded end enters a threaded hole in the upper frame part, A', thus securing the two parts together. The face-plate L is secured to the frame-piece A at the rear end by a projection, l⁵, which fits under a lip or projection, l⁶, on the frame A', and at its front end by screws l'. In this way a single pair of screws is sufficient to hold the face-plate in place, and it may therefore be easily removed. The ribbon-case Q' being secured to the face-plate, it 75 may be removed with the latter.

The base A of the frame is provided with a projecting wing, A⁷, having a slot or slideway, 80 f, for the sliding key.

The space between the lines stamped by the machine for the destination-station and the class and date of the ticket leaves room for the other matter which may be desired to be printed on the ticket.

The number of the type rings D employed should be sufficient to set up or form the name of any station desired. As shown in the drawings, fifteen type-rings are used, and this is ordinarily sufficient, as the names of few stations have more than fifteen letters; but a greater or less number of rings may be employed.

I claim—

1. The combination, in a railway-ticket stamp, with a series of revoluble type-rings mounted upon a horizontal cross-shaft for printing the name of the destination-station, of a revoluble cylinder, K, having a number of faces, k, for printing the class or character 90 of the ticket, a set of revoluble dating-wheels mounted on a shaft at right angles to the shaft of said type-ring, and a die-plate, O, said cylinder K being mounted parallel to the shaft of said type-rings and between the type-rings 105 and said dating-wheels, substantially as specified.

2. The combination, with a rotatable shaft, B, of a series of type-rings, D, having a frictional or yielding connection with said shaft and provided with recesses, and a sliding key entering said recesses and having an adjustable opening adapted to register with said type-rings, 110 substantially as specified.

3. The combination, with a rotatable shaft, B, of a series of type-rings, D, having a frictional or yielding connection with said shaft and provided with recesses, a sliding key entering said recesses and having an adjustable opening adapted to register with said type-rings, 120 and a series of movable stops to arrest the revolution of said type-rings when turned to a certain point, substantially as specified.

4. The combination, with a rotatable shaft, B, of a series of type-rings, D, having a frictional or yielding connection with said shaft and provided with recesses, a sliding key entering said recesses and having an adjustable opening adapted to register with said type-rings, 125 and a series of movable stops to arrest the 130 revolution of said type-rings when turned to a certain point, said type-rings having pins or

- projections fitting in annular channels in the adjacent rings to engage said movable stops, substantially as specified.
5. The combination, with a series of revolving type-rings, of a series of movable stops or fingers connected together, adapted to arrest the revolution of said rings at a certain point, substantially as specified.
6. The combination, with a series of revolving type-rings having pins or projections, of a series of movable stops adapted to engage said pins or projections and arrest the movement of said type-rings, substantially as specified.
7. The combination, with a series of revolving type-rings having pins or projections, of a series of movable stops adapted to engage said pins or projections and arrest the movement of said type-rings, said type-rings having annular channels in which said pins or projections fit, substantially as specified.
8. The combination, with a rotatable shaft, B, of a series of type-rings, D, having a frictional or yielding connection with said shaft and provided with notches or recesses in their periphery, and a sliding key, F, having notch f' and slide f^2 , for extending the width of said notch, substantially as specified.
9. The combination, with a rotatable shaft, B, of a series of type-rings, D, having a frictional or yielding connection with said shaft and provided with notches or recesses in their periphery, a sliding key, F, having notch f' and slide f^2 , for extending the width of said notch, and pivoted handle F', having lug f^4 , engag-
- ing a recess, f^5 , in said key F, substantially as specified.
10. The combination, with a rotatable shaft, B, of a series of type-rings, D, having a frictional connection with said shaft and provided with recesses, a sliding key adapted to enter said recesses in said type-rings and having an opening to register with one of said type-rings, said key being furnished with a series of notches, and a spring-pawl to regulate the movement of said key, substantially as specified.
11. The combination, with a series of revolving type rings or wheels having recesses, of a sliding key having an opening adapted to register with one of the type-rings and provided with a series of notches, and a spring-pawl, substantially as specified.
12. The combination, with a series of revolute type-rings provided with recesses, of a sliding key having an adjustable opening adapted to register with said type-rings, substantially as specified.
13. The combination, with a series of revolving type-rings provided with locking notches or recesses, of a sliding key, F, having notch f' or recess f^4 , and slide f^2 , for extending the width of said notch or recess, substantially as specified.

ALEXANDER D. JOSLIN.
